UNITED STATES PATENT OFFICE.

FRANK P. JOHNSON, OF DANVILLE, PENNSYLVANIA.

DESIGN FOR AN ANTIRATTLER.

SPECIFICATION forming part of Design No. 28,849, dated June 14, 1898.

Application filed November 27, 1897. Serial No. 660,012. Term of patent 14 years.

To all whom it may concern:

Be it known that I, FRANK P. JOHNSON, of Danville, in the county of Montour and State of Pennsylvania, have invented and produced a new and original Design for an Antirattler, of which the following is a full, clear, and exact specification.

The invention relates to attachments for thill-couplings.

Reference is to be had to the accompanying drawing, forming a part of this specification, in which the figure is a perspective view of an antirattler, showing my design.

The leading feature of my design consists

of a loop A, standing at an angle to shanks 15 B, terminating in coils C, from the ends of which extend arms D in an opposite direction to the shanks B, and the outer ends of said arms are curved back upon themselves to form loops E. 20

I claim—

A design for an antirattler for thill-couplings, as herein shown and described.

FRANK P. JOHNSON.
